UNITED STATES PATENT OFFICE.

WILLIAM J. STEENROD, OF BENTON HARBOR, MICHIGAN, ASSIGNOR TO BAKER-VAWTER COMPANY, OF BENTON HARBOR, MICHIGAN, A CORPORATION OF MICHIGAN.

LOCK FOR LOOSE-LEAF BINDERS.

Application filed August 30, 1926. Serial No. 132,403.

My invention relates to loose leaf binders, and is particularly adapted for use in that type of binder in which the two binder back members to which are hinged the binder covers are equipped with telescoping members arranged to engage orifices in the binder leaves, and in which means are provided for locking the bars at any distance apart permitted by the telescoping connecting members. The object of my invention is to provide a simple and efficient locking mechanism presenting no projecting operating member and released by a detached key member which affords the protection of a lock and prevents unauthorized removal or change of the leaves secured between the binder back members. With this object in view I have designed and invented the binder lock mechanism hereinafter described in detail, the essential elements of my invention being more particularly pointed out in the appended claims.

In the drawing, Figure 1 is a face view of a pair of binder back members to which my invention is shown applied; Fig. 2 is an end view of the same, and Fig. 3 is a section of the locking mechanism to which my invention relates, in a plane indicated by the dotted line 3—3 of Fig. 1, and on a larger scale than Figs. 1 and 2.

Like reference characters indicate like parts in all the figures of the drawing.

The specific construction of the binder back and telescoping members forms no part of my present invention, but by way of description of the structure to which my invention is shown applied, it may here be explained that the covers 1—1 are hinged to binder back members 2—2 to which are secured the upper post bar 3 and lower post bar 3^a to which the telescoping posts 4^a and tubes 4 are respectively secured, the positions of the parts mentioned referring to the positions of the parts in the drawing.

To the post bar 3, in the present instance midway of the length thereof, is fixed a tubular member 5, the free end of which is contracted to present an inclined or conical inner face. As illustrated the upper end of the tube 5 is shouldered and the reduced upper end, which seats snugly into a hole drilled in the bar 3, is turned against the beveled top edge of the hole to lock the tube securely in position.

The upper binder back member 2 is formed with a circular hole or orifice 6 coaxial with the tube 5, but of lesser diameter than the bore of the tube, thus providing an annular ledge extending marginally around the orifice which serves as an abutment for a coiled compression spring 8 which bears against the upper end of a ball-carrier 9 forming a portion of a ball-clutch mechanism. The lower hollow main portion of the ball-carrier is formed with an axial bore and has a coned lower outer face, and is provided with transverse bores (three in the present instance) for the reception of clutch balls 10 which cooperate with the inclined inner face of the tube 5, and also cooperate with a post 11 which is secured to the lower post bar 3^a and is disposed coaxially of the tube 5 within the bore of the ball-carrier.

The reduced upper end of the ball-carrier, marked 5^a, is a threaded stem adapted to cooperate with the interiorly-threaded reduced lower end or stem 12^a of a knurled key member 12, which stem is adapted to be inserted through the orifice 6 of the upper binder back member, and inside of the coiled spring 8.

As will readily be understood from the foregoing description, the binder back members may be pressed together to engage a group of interposed sheets, but relative movement of such members in the opposite direction will be prevented by the clutching engagement of the balls with the interior inclined face of the tubular clutch member 5, and with the post 11. When it is desired to remove the leaves, the stem portion of the key member 12 is engaged with the portion 5^a of the ball carrier and turned by the outer operating portion until the shoulder between such stem portion and the body of the key contacts with the face of the binder back member, and upon further turning, the key then draws the ball-carrier outwardly until the balls are released from clutching engagement, thus permitting the separation of the binder members. It will be noted that the threaded stem 5^a of the ball-carrier lies below or within the plane of the binder back member; and as it is round it is very difficult to get hold of with any kind of tool other than the key made for the purpose.

This key may be kept in the possession or

control of an authorized person, and removal of the sheets by an unauthorized person is thus rendered difficult.

I claim:

- 5 1. A ball-clutch mechanism for a pair of separable binder back members including a tube secured to one binder back member and formed with an interiorly coned end, a coaxially disposed post secured to the other binder back member, a ball-carrier having a hollow main portion coaxially arranged around said post within said tube and having a reduced threaded stem portion lying within the plane of said first-mentioned binder back member, 30 said ball-carrier being equipped with clutch balls and said first-mentioned binder cover member being orificed in alignment with said threaded stem of said ball-carrier; and a key member having a reduced internally threaded portion arranged to cooperate with said threaded stem portion of said ball-carrier through the orifice in said binder cover member and an outer operating portion arranged to bear on the outer face of 35 said binder cover member.
- 10 15 20 25 2. In combination, a ball-clutch mechanism for a pair of separable binder back members including a tube secured to one binder back member and formed with an interiorly coned end, a coaxially disposed post secured to the other binder back member, a ball-carrier having a hollow main portion coaxially arranged around said post within said tube and having a reduced threaded stem portion lying within the plane of said first-mentioned binder back member, 30 said ball-carrier being equipped with clutch balls and said first-mentioned binder cover member being orificed in alignment with said threaded stem of said ball-carrier; and a key member having a reduced internally threaded portion arranged to cooperate with said threaded stem portion of said ball-carrier through the orifice in said binder cover member and an outer operating portion arranged to bear on the outer face of 35 said binder cover member.

nism for a pair of separable binder back members including a tube secured to one binder back member and formed with an interiorly coned end, a coaxially disposed post secured to the other binder back member, a 30 spring-pressed ball carrier having a hollow main portion coaxially arranged around said post within said tube and having a reduced threaded stem portion lying within the plane of said first-mentioned binder back member, 35 said ball-carrier being equipped with clutch balls and said first-mentioned binder cover member being orificed in alignment with said threaded stem of said ball-carrier; and a key member having a reduced internally 40 threaded portion arranged to cooperate with said threaded stem portion of said ball-carrier through the orifice in said binder cover member and an outer operating portion arranged to bear on the outer face of 45 said binder cover member.

In testimony whereof, I have subscribed my name.

WILLIAM J. STEENROD.
